DESIGN FOR A CIGARETTE DISPENSER OR THE LIKE

Monroe B. Toklas, New York, N. Y., assignor to Clearite Products, Inc., New York, N. Y.

Application May 16, 1945, Serial No. 119,564

Term of patent 3½ years

(Cl. D85—2)

To all whom it may concern:

Be it known that I, Monroe B. Toklas, a citizen of the United States of America, residing in New York city, county of New York, and State of New York, have invented a new, original, and ornamental Design for a Cigarette Dispenser or the like, of which the following is a specification, reference being had to the accompanying drawing, forming part thereof, wherein, rette dispenser or the like, showing my new design.

I claim:

The ornamental design for a cigarette dispenser or the like, substantially as shown.

MONROE B. TOKLAS.
